Design for Clock Case
Patented July 16, 1887

Peter Binguine's Design for Clock Case

Des. 916

Pietro Linguini, of West Haven, Conn.
Letters Patent No. 916, Dated July 14, 1857.

The schedule referred to in the Letters Patent, and making part of the same.

To all whom it may concern:

Be it known that I, Pietro Linguini, of West Haven, in the County of New Haven, and State of Connecticut, have invented or produced a new and original design for clock cases, which I term the "Continental"; and I do hereby declare that the following is a full, clear and exact description of the same; reference being had to the accompanying drawing, making a part of this specification, said drawing being a front view of a clock case, constructed according to my design.

My design consists in having the clock case made in the form of a pretty human figure, dressed in the military costume worn by the Continental or provincial troops during the American Revolution.

The circular opening for the dial A, is made in the chest and abdomen of the figure; and the arms B, and hands C, are so disposed as to hold the dial A, or rather, are so represented.

The coat D, breeches E, stockings F, and buckled shoes G, are of the well known military style of the period mentioned, and also the three-cornered or "cocked hat" H. The figure is placed upon a base I. The head J, of the figure is provided with a wing K, and the shirt bosom is provided with a full L, and plaits M.

Having thus described my design, what I claim as new, and desire to secure by Letters Patent, is

The figure dressed in the military costume as herein shown and described, and forming a new and original design for a clock case.

Witness,

Daniel H. Platt
T. B. Rawson
